UNITED STATES PATENT OFFICE.

ALWIN G. STEINMAYER, OF MILWAUKEE, WISCONSIN, ASSIGNOR TO LINE MATERIAL COMPANY, OF SOUTH MILWAUKEE, WISCONSIN, A CORPORATION OF WISCONSIN.

ELECTRIC SWITCH.

Application filed August 13, 1925. Serial No. 50,024.

This invention relates to certain new and useful improvements in electric switches and refers more particularly to a disconnecting switch adapted to be incorporated within a 5 high voltage transmission line to facilitate the disruption of a section of the line for the purpose of repairing or replacement. The switch is generally mounted upon a tower, pole or other support and is usually 10 controlled with two similar units by a single device located at a remote point.

Switches of this character are designed to carry considerable current and as a result necessitate the provision of a quick make 15 and break to eliminate destructive arcing forces. It is also highly desirable that the gap between the switch parts when in open position be as wide as possible to prevent the jumping of the current thereacross.

20 It is therefore an object of my invention to provide an improved switch construction of the character described in which the movable member has a relatively high speed of break to eliminate as much as possible the 25 destructive arcing forces.

Another object of this invention resides 30 in the provision of an improved switch construction wherein the movable member may be swung through approximately ninety degrees or more which is contrasted with the switches of this type now on the market in which the movable member swings through but approximately seventy degrees.

Switches of the character described are 35 generally located in the open and are thus exposed to the elements and in winter time sleet and ice frequently accumulate on the contacts to thus make opening movement difficult. These switches are also designed 40 to be inoperative for relatively long periods of time as a result of which there is a normal tendency of the movable parts to freeze and this invention has as another object the provision of an improved switch construction 45 wherein the opening movement of the switch is facilitated to break any tendency of the parts to hold together. Any tendency of the parts to freeze to prevent or restrain opening movement is overcome by providing a loosely pivoted member on the free end 50 of the switch movable member which provides a contact portion having a pivotal movement in the opening operation to thus break any tendency of the parts to freeze 55 together.

It is a further object of this invention to provide an improved sleet hood in which a laminated spring contact is fixed to provide a good electrical connection with the end of the switch member projectable into the 60 hood in closing.

A still further object of this invention resides in the provision of an improved switch construction of the character described in which the switch member proper is formed 65 in a plurality of parts hingedly connected and adapted to be in approximate longitudinal alignment when closed and to move at an angle to each other in opening to thus produce a relatively quick opening move- 70 ment.

With the above and other objects in view which will appear as the description proceeds, my invention resides in the novel construction, combination and arrangement of 75 parts substantially as hereinafter described and more particularly defined by the appended claims, it being understood that such changes in the precise embodiment of the hereindisclosed invention may be made as 80 come within the scope of the claims.

In the accompanying drawings, I have 85 illustrated one complete example of the physical embodiment of my invention constructed according to the best mode I have so far devised for the practical application of the principles thereof, and in which:

Figure 1 is a side view of a switch unit constructed in accordance with my invention, parts thereof being broken away and 90 in section in order to more clearly illustrate structural details;

Figure 2 is an enlarged fragmentary detail view illustrating the manner of connecting the parts of the switch member and 95 of producing the relative movement between the parts;

Figure 3 is a view looking at my improved switch construction on the plane of the line 3-3 of Figure 1, and 100

Figure 4 is an enlarged, fragmentary, detail view of the sleet hood or housing and illustrating a slightly modified manner of forming the electrical connection between the movable switch member and the stationary contact, said view being partly in section and partly in elevation.

Referring now more particularly to the accompanying drawings, in which like numerals designate like parts throughout the 110

several views, the numeral 5 represents a mounting base of channel iron or the like, which may be part of the tower or other support for the switch unit and on which 5 two pedestals 6 are mounted by being bolted or being otherwise secured, as at 7. The base or supports 8 of suitable insulators 9 and 10, preferably of the petticoat type, are bolted or otherwise secured to the pedestals, 10 as at 11. As clearly illustrated, the insulators are spaced and when the switch unit is mounted in the vertical they are preferably directed upwardly at an angle to provide the proper electrical clearance. 15 Cemented or otherwise fixed on the outer ends of the insulators 9 and 10 are heads or caps 12 and 13, respectively, and to the cap 12 is bolted or otherwise secured an angle bracket 14 on which is mounted the 20 stationary contact terminal 15 of the switch, the bracket 14 being directed at an angle to position the terminal in approximate parallel relationship with the base 5. In this form of my invention the contact terminal 25 is preferably in the form of a housing or sleet hood 16 in which one or more spring contacts 17 are fixed to receive the contact end portion 18 of the movable switch member 19, to be later described, the transmission line 20 being connected with the stationary contact terminal and the clips by a 30 socket terminal 21 bolted or otherwise fixed to the terminal lug 22 of the contact 15. The other insulator 10 has a hinge bracket 35 or arm 23 fixed to its head 13 which is preferably directed at an angle to the axis of the insulator, as illustrated. The movable switch member 19 is preferably formed in two parts or sections 24 and 25 which overlap at their adjacent ends and are connected by a pivot 26, the lower end of the part or section 25 being pivoted, as at 27, to the bracket or arm 23 in approximate alignment with the contact terminal 15. As best 40 illustrated in Figure 2, the inner or lower end of the switch member section 24 is extended angularly beyond its pivot 26, as at 28, and has pivotally connected therewith eccentrically with respect to pivot 26, as at 45 29, the upper or inner end of a link or arm 30, the lower or outer end of which is pivotally connected, as at 31, with the outer end 32 of the bracket or arm 23 which extends beyond the pivot 27, as illustrated in 50 Figure 1. The link or lever 30 being mounted as described intersects or crosses the movable switch member section 25 between its pivots 23 and 26 so that a movement of the 55 section in one direction produces a corresponding movement of the section 24 in the same direction on its pivot 26 at a relatively greater speed, the difference in speed being produced by the differences in the distances between the axes of the pivots 26 and 29, and 60 65 27 and 31.

Opening and closing movements are imparted to the movable switch by an actuating member or lever 33 which is fixed to an operating shaft 34 suitably journaled in bearings 35 fixed to the mounting base 5 70 and adapted to be rotated from an operating lever, not shown, connected with a rod 36, the upper end of which is pivotally connected, as at 37, with a lever 38 also fixed to the shaft. A mounting member 39 is pivotally connected, as at 40, with the free end of the actuating member and carries the support 41 of an actuating insulator 42, preferably of the petticoat type and having a cap 43 cemented or otherwise fixed to its 80 outer end and carrying an angular bracket 44 between the arms or lugs 45 of which the switch member is pivotally secured by the pivot 26 connecting the parts 24 and 25 thereof. The insulator 42 is also inclined 85 at an angle to the horizontal to provide the necessary electrical clearance, as is well known to those skilled in the art.

The sections of the switch members are preferably formed of two or more spaced 90 members to give added rigidity and the members comprising the outer-most section 24 converge and pivotally receive therebetween the contact member 18 which is of the knife blade type and is connected therewith by a pivot 46. The knife blade contact 18 is normally urged to its dotted line position illustrated in Figure 1 by a contractile spring 47 having one end secured to a pin 48 connecting the sides of the switch section 24 and its other end connected, as at 49, with the extended end of a terminal member or clamp 50 which is electrically connected with the contact. The clamp 50 affords means for connecting one end of a 100 lead 51 with the contact 18, the other end of the lead being electrically connected with a line 52 by being confined between a socket terminal 53 and a terminal lug 54 extended from the bracket arm 23, the lead 51 being 105 flexible and insuring against dielectric loss and the necessity of providing electrical connections between the switch member sections, although the switch member when closed assists in carrying a portion of the 110 load.

Assuming the switch to be in its closed position illustrated in full lines in Figure 1, an upward movement of the operating rod 36, as illustrated in dotted lines, 120 causes the actuating member and insulator to press outwardly on the switch member at the point of pivotal connection of its sections 24 and 25, and the switch member is swung to the right with reference to the 125 drawing by reason of the direct outward push on the pivot 26 and the upward stress on the pivot 29 transmitted thereto through the link 30 which is compressed against the solid pivot 31. If the contact blade 18 has 130

become frozen between the spring contacts 17, the pivotal movement of the blade on its pivot 46 makes the breaking thereof easy so that no undue stress need be applied to the 5 operating rod for the opening movement.

During the opening movement the switch member section 25 moves on its pivot 27 in proportion to the movement of the actuating member, but the section 24 thereof, instead 10 of remaining in longitudinal alignment with the section 25, is swung on its pivot 26 in the same direction, but at a greater speed, its movement on its pivot being greater than the movement of the section 25 on its pivot 15 as the pivots 26 and 29 are closer together than the pivots 27 and 31. The switch member is thus given a compound or double movement to produce a very quick opening movement.

20 As is usual in switches of this construction, arcing horns 55 are provided to break the circuit and thus relieve the contacts 17 and 18 of the destructive arcing that takes place at the breaking of a high voltage circuit. One horn 55 is preferably fixed to the sleet hood 16 by a clamp device 56 and the other is adjustably secured to the switch member section 24 by a clamp device 57, the horns being so shaped and positioned as to 25 be under tension prior to their separation to thus cause the break to occur with a quick, snappy action.

In Figure 1, the switch is shown by dotted lines in partly open position and in full 35 open position the switch section 24 is in a position of approximately ninety degrees with respect to its fully closed position, which is very desirable in switches of this character. This has not been accomplished 40 satisfactorily in prior devices, as to produce such movement it has been necessary to move the operating member through too great a distance.

In closing, the operation of the switch is 45 reverse to that just described and the contact member 18 which is held in its dotted line position illustrated in Figure 1 strikes the bottom portion 58 of the sleet hood which extends beyond the opening of the 50 hood and is so arranged that the contact rides into the sleet hood between the spring contacts.

In Figure 4, a slightly modified type of 55 electric connection between the movable switch and its contact terminal is illustrated in which the spring clip contacts 17 are eliminated and in their place a contact 59, preferably of laminated spring copper or other material, is secured therein with one 60 end clamped in the inner portion of the sleet hood between a flange or projection 60 therein and the rear wall of the hood, the other end of the contact being curved over the flange 60 to its dotted line position illustrated. The knife blade portion 18 of the

movable switch member has its end in the shape illustrated in the drawing which is biased with respect to its length with its under nose portion 61 curved and provided with a rounded knob or projection 62. In 70 closing the grooved portion 61 rides on the extended part 58 of the sleet hood engaging its biased cut end with the end of the spring contact 59 rocking thereunder on its curved portion until the knob 62 engages the projection 58, when the end is raised to move the contact to its full line position and maintain the same under tension. The laminated contact portion 59 is removable from the sleet hood and is readily detachably secured in position by a set screw or other clamping device 63.

From the foregoing description taken in connection with the accompanying drawing it will be readily apparent to those skilled 85 in the art to which an invention of this character appertains that I have provided a generally improved and efficient switch construction which is especially adapted for handling high tension current and one in 90 which any number of units may be operated simultaneously by a single operating rod 34.

I claim:

1. In combination, a switch member including two sections having their adjacent 95 ends pivotally connected, means pivotally mounting the outer end of one switch member section, a contact terminal with which the outer end of the other switch member section is engageable, means for imparting 100 opening force to the switch member, said force being applied at the point of pivotal connection of the sections, and means whereby the outer section travels faster than the inner section during opening movement of 105 the switch member.

2. In combination, a switch member including two sections having their adjacent 110 ends pivotally connected, means pivotally mounting the outer end of one switch member section, a contact terminal with which the outer end of the other switch member section is engageable, means for imparting 115 opening force to the switch member, said force being applied at the point of pivotal connection of the sections, whereby the leverage at the initial opening movement is substantially equal to the length of the first-mentioned section, and means whereby the second-mentioned section travels faster than 120 the first-mentioned section during opening movement of the switch member.

3. In combination, a switch member including two sections having their adjacent 125 ends pivotally connected by a common pivot, means pivotally mounting the outer end of one switch member section, a contact terminal with which the outer end of the other switch member section is engageable, an actuating member located adjacent the com- 130

mon pivot of the switch member sections, means connecting the actuating member with the first-mentioned switch member section, a link, means pivotally connecting the link with the second-mentioned switch member section to one side of the common pivot, and means pivotally mounting the other end of said link to the other side of the pivotal mounting of the first switch member section, 10 whereby movement of the actuating member to open the switch causes the first switch member section to swing on its pivot carrying with it the second switch member section and at the same time the second switch 15 member section is swung on its pivotal connection with the other switch member section in the same direction through the medium of said link.

4. In combination, a two-part movable switch member, an operating member, a single pivot connecting the adjacent ends of the switch member parts and the operating member with the switch member, a contact terminal with which one end of the switch 20 member is engageable, a pivotal mounting for the other end of the switch member, a lever and means pivotally connecting one end of the lever with the first mentioned switch part and means connecting the other 25 end thereof with the pivotal mounting.

5. In a switch construction, a contact terminal including a sleet hood, a spring contact member of approximately U-shape having one end thereof secured within the hood, 30 a movable switch member, a contact portion movably mounted on the switch member and engageable with the other end of said U-shaped spring contact in closing, and

means whereby the contact portion is moved with respect to the movable switch member 40 to move the U-shaped spring contact under tension and thus provide a good electrical connection between the switch member and contact.

6. In a switch construction, a contact terminal including a sleet hood, a spring contact member of approximately U-shape having one end thereof secured within the hood, a movable switch member, a contact portion on the switch member engageable with the 45 other end of said U-shaped spring contact in closing to move the same under tension and thus provide a good electrical connection between the switch member and contact, means pivotally connecting the contact portion of the switch member with the switch member proper, and means on said contact portion adapted to place said spring contact under tension as the switch member is closed.

7. In combination, a switch member including two sections, a single pivot connecting the adjacent ends of the two sections, means pivotally mounting the outer end of one section, a contact terminal with which the outer end of the other section is engageable, the switch sections being arranged end to end and in the same plane when the switch is closed, means connected with the first-mentioned section for opening the 65 switch, and means becoming active upon opening movement of the switch to cause the second-mentioned section to assume a position at an angle to the first section.

In testimony whereof I affix my signature.
ALWIN G. STEINMAYER.
